SAW FILING DEVICE

Wilfred L. La Clair, Rochester, N. Y.

Application October 23, 1947, Serial No. 781,714

3 Claims. (Cl. 76—36)

1

The object of this invention is to provide a tool that can be used to hold a three cornered file in the correct angular position while it is being used to push the file back and forth in the filing of the teeth of a saw.

Another object of the invention is to provide the tool with a so-called pendulum which is connected rigidly to the tool so that it will hang straight down when the three cornered file rests in the triangular space between two teeth of the saw.

Another object of the invention is to provide means for clamping the so-called pendulum in its correct position after the three cornered file has been engaged between two teeth of the saw to be filed.

Another object of the invention is to provide the tool with a handle swiveled thereon by which the tool can be moved back and forth so that the handle cannot disturb the angular position of the file with reference to the teeth of the saw being filed.

These and other objects of the invention will be illustrated in the drawings, described in the specification and pointed out in the claims at the end thereof.

In the drawings:

Figure 1 is a side elevation of the complete tool assembled ready for use.

Figure 2 is an enlarged end elevation of the tool partly broken away, looking at it from the left of Figure 1, the file being sectioned away, and the pendulum being partly broken away.

Figure 3 is a vertical section on the line 3x, 3x of Figure 2.

Figure 4 is a side elevation of the bracket with the cylinder removed therefrom.

Figure 5 is an end elevation of the metal cylinder and its metal core showing the socket into which the tang is inserted.

In the several figures of the drawing like reference numerals indicate like parts.

The teeth of hand saws require sharpening from time to time and it is well known that they are sharpened by filing them with a triangular or three cornered file. This file is ordinarily set rigidly in a hole provided in a wooden handle which handle is moved forward and back by hand. In such case the accuracy of the filing depends on the steady hand that holds the file.

The object of my invention is to make the steady hand unnecessary.

In the drawing showing my invention reference numeral 1 indicates a three cornered file. All such files have a tapered shank of reduced size 55

2

that is forced into a suitable hole provided in a wooden handle. This tapered shank of the file is ordinarily called a tang.

For the purpose of my invention I provide a hollow metal cylinder 2 which is filled with a wooden core 3. This wooden core is provided with a socket 4 into which the tang 5 of the file is inserted. This socket is shown in end elevation in Figure 5.

10 This cylinder 2 in turn is held in a bracket 6 having a socket 7 therein, which is adapted to hold the cylinder 2 with its core 3.

This socket is cut away on the under side with a transverse slot as indicated at 8 to receive a 15 U-shaped yoke or bolt 9 that nests into the bracket and makes direct contact with the cylinder 2 on its under side.

On the sides of the bracket are provided the lugs 10 and 11. The lugs are perforated from top 20 to bottom and from below the open ends of the U-shaped yoke or bolt 9 extends up through these holes. The open ends of the U-shaped bolts are threaded with male threads. These threaded ends are engaged with wing nuts 12 and 13 by 25 which the underside of the bolt is drawn up into the slot 8 so that it makes contact with the under side of the cylinder 2 and rigidly fastens the cylinder in any desired angular position with reference to the bracket 6. This angular adjustment

30 of the cylinder 2 can be made either before or after the file is inserted in the core, but would ordinarily be made after the file is inserted in the core of the cylinder than before it is inserted. This adjustment fixes the position of the edge of the file transversely to the pendulum which must always be permitted to hang straight down, it being understood that the edge of the file is held at the bottom of the tooth being sharpened, or that the surface of the file is held against 40 the surface of the tooth being sharpened.

On the under side of the bracket 6 is provided a lug 15, which extends transversely of the bracket. This lug is hollow and carries a bolt 16 therein having a head 17 on the right hand end 45 of it and a nut 18 threaded on the left hand end thereof as shown in Figure 2.

A large oval hole or slot 19 is formed in the bottom of the lug 15 and on the under side of the shank 20 of the bolt is formed a hole 21 threaded with a female thread. Into this hole 21 is threaded the end of the stem 22 which at its upper end is threaded with a male thread. On the lower end of the stem 22 is provided a weight 23, making the stem and weight a so-called pendulum.

Extending centrally from the right hand end of the bracket as shown in Figures 1 and 3 is a stem 24. This stem is locked in place in the bracket 6 by a set screw 25. On this stem is provided a handle 26 which is swiveled thereon so that the handle can turn freely on the stem, or the stem can turn freely in the handle.

With the parts assembled as above described, the stem 22 should extend down from the bracket 6 and the bolt 16 should be fastened in the lug 10 by the nut 18.

It will be understood that the so-called pendulum which includes the stem 22 and the weight 23 can be moved forward and back, rotating the bolt 16 in the lug 15. If it moves sideways it will 15 rotate the bracket 6 with it.

The bracket with its handle and file can be moved forward and back horizontally or with the file tilted up at any angle that may be desired by the filer. If the bracket and its assembly is tilted up while filing, then the pendulum should be put in a vertical position or as near to a vertical position as the fixtures that hold the saw will permit. This tilting of the bracket and its file and its handle is indicated by the center line 27 which center line indicates the position of the axis of the whole assembly; namely, the bracket, the file and the handle. The pendulum will be held stationary in a vertical position while the assembly is being tilted, thus changing the angular relation between the pendulum and the bracket 6 and the rest of the assembly as shown in Fig. 1, the pendulum is clamped by the bolt 16 and nut 18 at 90° to the axis of the file, but this angle can be increased within the limit of the slot 19, as indicated by the dotted line in Fig. 1.

In the use of this invention, the file will be placed on the teeth so as to nest between two adjacent teeth of the saw to be filed and the thumb nuts 12 and 13 will be loosened up so that the bracket 6 can be turned on the cylinder 2, so that the pendulum will hang straight down therefrom as shown in the three figures.

The cylinder 2 and the bracket 6 will then be clamped firmly together by the thumb nuts 12 and 13. Thereafter the file in its backward and forward movement will be held in its correct angular position by the pendulum. The handle 26 being swiveled on the bracket cannot disturb this correct angular position of the file while it is being moved back and forth, no matter how much the hand of the filer or operator may turn. In this way the control of the position of the bracket that holds the file is taken away from the hand of the operator because the handle is swiveled and the file is therefore always held in the same position by the pendulum.

I claim:

1. In a saw filing device the combination of a hollow bracket having a cylindrical hole therein, a cylinder mounted in said cylindrical hole, said cylinder having a core therein adapted to hold a file by its tang in line with the cylinder, means for holding said cylinder from turning in said bracket, a handle on said bracket, in line with said cylinder, said bracket having a lug extending downwardly on the bottom thereof, said lug

having a round opening therein extending transversely of the axis of the cylinder, a bolt filling said round opening and having a head on one end and a nut on the other end, by which it is clamped axially in said lug, an oval opening in the bottom of said lug below said bolt, a stem engaging said bolt thru said oval opening and extending downwardly therefrom, a weight on the lower end of the stem adapted by gravity to hold the bracket from turning on its axis, said oval opening permitting the pendulum to be clamped in position at 90° or more to the axis or edge of the file, the whole assembly being adapted to be moved back and forth in filing the teeth of a saw.

2. In a saw filing device the combination of a hollow bracket having a cylindrical hole therein, a cylinder mounted in said cylindrical hole, said cylinder having a core therein adapted to hold a file by its tang in line with the axis of the cylinder, said bracket being cut away on the underside with an arcuate slot, a U-shaped bolt having two threaded ends nested in said slot and making contact with said cylinder, lugs on either side 25 of said bracket through which the threaded ends of said bolt extend upwardly, nuts engaging the said threaded ends to draw the U-shaped bolt up against its cylinder and its core to clamp them in the bracket, a handle swiveled on said bracket and adapted to turn thereon independent of the bracket, a pendulum attached to said bracket and adapted to hold the bracket and file in a predetermined angular position.

3. In a saw filing device, a housing having two cylindrical openings therein, one of said openings being at right angles to and below the other opening, a cylindrical core mounted in the upper opening, an open half round slot cut in the under side of the upper portion of the housing, lugs on either side of said housing near the top thereof, a U-shaped bolt engaging with said slot and lugs and wing nuts resting on said lugs clamping the bolt in the slot against the core in the upper part of the housing, a bolt in the cylindrical opening in the lower part of the housing, an oval slot cut around on the lower side of the cylindrical opening, a stem engaging the bolt through said slot with a threaded engagement, said stem being capable of swinging along the oval slot to 50 any angular position therein, a nut on said bolt for clamping the bolt and stem in any desired angular position with reference to said slot.
